Inventor

D. D. Price

By *A. Randolph Jr.*, Attorney

UNITED STATES PATENT OFFICE.

DAVID D. PRICE, OF NORMAN, OKLAHOMA.

BOAT-OAR.

1,346,554.

Specification of Letters Patent. Patented July 13, 1920.

Application filed October 1, 1919. Serial No. 327,617.

To all whom it may concern:

Be it known that I, DAVID D. PRICE, a citizen of the United States, residing at Norman, in the county of Cleveland and State of Oklahoma, have invented certain new and useful Improvements in Boat-Oars; and I do hereby declare the following to be a full, clear, and exact description of the invention, such as will enable others skilled in the art to which it appertains to make and use the same.

My invention relates to improvements in bow facing oars having novel means for reversing the direction of course on an oar whereby the operator of a boat may face the bow of the same while rowing.

An important object of this invention is to provide novel means for adjustably securing the oars to the sides of the boat whereby the oars may be adjusted in any desired position with relation to the oarsman.

A further object of the invention is to provide novel means for horizontally pivoting the oar intermediate its ends whereby the oar may be dipped in and out of the water.

A further object is to provide a bow facing oar which is simple, efficient, and cheap to install on row boats.

Other objects and advantages of the invention will be apparent during the course of the following description.

In the accompanying drawings forming a part of this application and in which like numerals are employed to designate like parts throughout the same,

Figure 1 is a plan view of a row boat having my improved bow facing oars applied,

Fig. 2 is a vertical section taken on line 2-2 of Fig. 1,

Fig. 3 is a horizontal section through the reversing mechanism of the oar,

Fig. 4 is a vertical section taken on line 4-4 of Fig. 1, and,

Fig. 5 is a detail view of the oar fastening means.

In the drawings, wherein for the purpose of illustration is shown a preferred embodiment of my invention, the numeral 10 generally designates a row boat having the usual gunwales 11 and transverse seats 12.

An elongated guide member in the form of a rod 13 is secured to each gunwale by depending brackets 14. Bolts 15 extend

through openings in the brackets and the adjacent portions of the gunwale.

A carriage 16 is mounted on each rod 13 and has connection with a pair of upstanding spaced parallel standards 17 having 60 their lower portions bifurcated as indicated at 18 and arranged on opposite sides of the carriage 16. The bifurcated portions 18 may be welded to or cast integral with the sleeve portion of the carriage 16. Set 65 screws 19 have threaded engagement with the sleeve portion of the carriage and engage the rods 13 for securing the carriage in an adjusted position. The standards 17 carry a shaft 20 having one end portion 70 provided with a polygonal nut 21. A set screw 22 is carried by one of the standards 17 and engages the shaft 20 to prevent the same from rotating.

A supporting plate 23 is provided with a 75 pair of spaced parallel depending bearings 24 in the form of apertured ears. The bearings or apertured ears 24 are horizontally pivoted to the shaft 20 inwardly of the standards 17, and they are equipped with compression oil cups 24^a.

The plate 23 is provided with coacting toothed segments 25 and 26 having attaching shanks 27 and 28 respectively. The toothed segments 25 and 26 are supported by upstanding pivot elements 29 extending through the plate 23 and secured to the same. Suitable washers 30 surround the pivot elements 29 and support a cover plate 31 in spaced relation to the segments 25 80 and 26. The upper end portions of the pivot elements 29 have threaded engagement with nuts 32 which serve to hold the cover plate and toothed segments in position.

An oar 33 is provided in its inner end portion with a slot 34 receiving the shank 27 of the toothed segment 25. Locking plates 35 have their end portions bent downwardly and over the sides of the oar 33 for 100 forming retaining flanges 36. Bolts 37 extend through the retaining flanges, the inner end portion of the oar and the shank portion of the toothed segment 25 for securely connecting the oar to the toothed segment. A 105 handle 38 is secured to the shank 28 of the toothed segment 26 as is the oar 33 secured to the shank 27.

In the practice of my invention, the rod 13 is secured to the gunwale of a boat and 110

the carriage is positioned at the desired point on the same. As is obvious from Fig. 1, the rearward movement of the handle of the oar forces the oar rearwardly and thereby propels the boat in the direction faced by the oarsman. In horizontally pivoting the oars I am enabled to dip them in and out of the water quite as freely as oars of the usual construction.

10 While I have shown and described the preferred embodiment of my invention, it is understood that such minor changes in arrangement and construction of parts may be made as will remain within the spirit of 15 the invention and the scope of what is claimed.

Having thus described my invention, what I claim is:—

1. An oar of the class described including 20 a support, a carriage adjustably carried by the support, a plate horizontally pivoted to the carriage, a pair of toothed segments vertically pivoted to the plate, and handles and oars secured to the segments.

25 2. An apparatus of the character described including a support, a carriage adjustably mounted on the support, a pair of coacting toothed segments carried by the plate, oars and handles secured to the 30 toothed segments, and a cover plate detachably arranged over said toothed segments in spaced relation to the same.

3. An apparatus of the character described including an elongated bar, a carriage having a sleeve surrounding the bar and provided with a pair of upstanding parallel standards, set screws carried by said sleeve and engaging said elongated bar for securing the carriage in an adjusted position, a base plate having a pair of depending apertured ears horizontally pivoted to said standards, toothed segments rotatably carried by the plate, and an oar and a handle rigidly secured to said toothed segments.

45 4. An apparatus of the character described including a support having an elongated bar and brackets for supporting the

elongated bar, a carriage adjustably secured to said support, a base plate having a pair of depending apertured ears horizontally pivoted to said carriage, upstanding pivot elements carried by said base plate, coacting segments rotatably connected to said pivot elements and provided with attaching shanks, and an oar and a handle secured to 55 said attaching shanks.

5. An apparatus of the character described including a support, a carriage adjustably carried by the support, a base plate horizontally pivoted to the carriage, coacting toothed segments carried by the base plate, and oars and handles secured to said toothed segments.

6. A bow oar including a support adapted to be secured to the gunwale of a boat, a carriage adjustably carried by the support, a pair of upstanding parallel standards carried by said carriage, a base plate pivotally mounted on said standards, a pair of toothed segments carried by said base plate, an oar 70 carried by one of said segments, a handle carried by the remaining segment, and a cover plate mounted above said base plate and parallel therewith.

7. A bow facing oar comprising a support 75 adapted to be secured to the gunwale of a boat, a base plate, a carriage adjustably mounted upon said support, means for securing said base plate upon said carriage, a cover plate spaced above said base plate, 80 a pair of toothed segments rotatably mounted between said base plate and said cover plate, an oar connected with one of said segments, a handle connected with the remaining segment, and means for securing 85 said carriage in adjusted position upon said support.

In testimony whereof I affix my signature in presence of two witnesses.

DAVID D. PRICE.
